COMBINATION PAINT BRUSH HOLDER, DRIP PAN AND SUPPORTING CLAMP

Lawrence C. Bennett, 125 Fernwood Court,
Santa Rosa, Calif. 95401

Filed Sept. 6, 1966, Ser. No. 3,739

Term of patent 14 years

(Cl. D9—2)

I claim:

The ornamental design for a combination paint brush holder, drip pan and supporting clamp, as shown.
